Patented Sept. 21, 1920.

UNITED STATES PATENT OFFICE.

ELBY A. MORRIS, OF LEETONIA, OHIO.

TROLLEY-RETRIEVER.

1,353,262.

Specification of Letters Patent. Patented Sept. 21, 1920.

Application filed June 25, 1917. Serial No. 176,796.

To all whom it may concern:

Be it known that I, ELBY A. MORRIS, a citizen of the United States, residing at Leetonia, in the county of Columbiana and 5 State of Ohio, have invented certain new and useful Improvements in Trolley-Retrievers, of which the following is a specification.

This invention relates to overhead trolley devices for electric railway cars, and more particularly to a novel improvement in trolley retrievers.

To this end, the invention contemplates a novel trolley pole and stand, of such construction that when the pole leaves the usual conductor wire and jumps upwardly, it will be automatically returned to a safety position, thus preventing the pole from striking the feed wire supports or pole arms, and 20 causing consequent damage.

A further object of the invention is to provide a simple and reliable construction which effectively holds the trolley pole in contact with the conductor wire under normal conditions, and which will quickly and 25 positively operate under emergency conditions to safeguard the trolley apparatus.

With the above and other objects in view which will more readily appear as the nature of the invention is better understood, 30 the same consists in the novel construction, combination and arrangement of parts hereinafter more fully illustrated and claimed.

A preferred and practical embodiment of 35 the invention is shown in the accompanying drawings, in which—

Figure 1 is a vertical sectional view showing the general arrangement and structural details of my improved device, the same being 40 in its normal condition.

Fig. 2 is a view similar to Fig. 1, but showing the relative position of the trolley pole after it leaves the conductor wire in full lines, and indicating the safety position 45 to which the same automatically falls in dotted lines.

Fig. 3 is a top plan view of the invention.

Similar references designate corresponding parts throughout the several figures of 50 the drawings.

In carrying out the present invention it is proposed to provide a base plate 1 of suitable dimensions, which may be readily positioned and secured upon the top of a car or 55 other vehicle by suitable fastening means.

This base plate is preferably formed with a relatively large centrally located upstanding bearing boss 2, and a pivot pin 3, which provide a pivotal bearing for a trolley pole stand designated generally as S.

As will be observed from Figs. 1 and 2 of the drawings, the trolley stand S comprises a frame including a bottom wall 4 provided with a recess 5 in its under side for receiving the upstanding bearing boss 65 2 of the base plate, and also has an opening 6 for permitting the pin 3 to project into an exposed position to receive a suitable clamping nut 7, for pivotally holding the entire frame of the base plate. At the lateral edges of the bottom wall 4 of the frame are provided the upstanding side walls 8—8, which may, for the sake of lightness and economy, be of the open or skeleton formation shown, and provide suitable bearings 75 for the axle bolt 9 of a rockable supporting member 10.

As will be observed from Fig. 3, this supporting member is preferably formed at its intermediate portion with the hub or oppositely disposed bolt receiving sleeves 11, while one end thereof is forked as at 12 to pivotally receive one end of a spring guide- 80 rod 13. This rod is surrounded by a coiled compression spring 14, one end of which 85 abuts against the forked end 12 of the supporting member 10, while the opposite end thereof abuts against a suitable bracket 15 which is secured to the opposite side walls 8 of the frame. For the purpose of holding 90 the end of the spring positively positioned in the bracket 15, the latter is also preferably provided with the guide pin 16, as will be clearly apparent from the several figures 95 of the drawing. With this arrangement of the spring 14, it will be apparent that the same will tend to rotate the supporting member 10 so that the head portion 17 thereof will have a tendency to swing in a clockwise direction.

Referring further to the supporting member 10, it will be observed that the head portion 17 thereof is provided on one side with a hinge knuckle 18, while the opposite side thereof is provided with the upstanding ears 105 19 for pivotally receiving therebetween a latch dog 20, which is provided at one end with a latch shoulder 21, while its opposite end 22 works against the tension of a spring 22. The hinged knuckle 18 of the support- 110

ing member carries therewith a socket element 23 which is preferably hollow to receive the trolley pole or standard 24, which as usual is provided with the trolley wheel 25 for engaging the line wire conductor C.

It will thus be understood that the socket element 23 carrying the pole 24 is hinged or pivoted to the supporting member 10, and for the purpose of maintaining the longitudinal axes of both the supporting member and the socket element or trolley pole in alinement, the said socket element is provided with a keeper shoulder 26 for engaging with the latch shoulder 21 of the latching dog 20. As will be observed from the drawings, the socket element 23 is further provided with an offset bracket arm 27, the extremity of which is connected by means of a spring 28 to a suitable eye 29 carried by the supporting member, as will be observed from Figs. 1 and 2. This spring has a tendency to swing the entire pole and socket element 23 on the hinge 18, which operates to not only maintain a firm engagement between the shoulders 26 and 21 but also compels the pole to drop into a safety position, as will hereinafter more fully appear.

Located between the opposite upstanding side walls 8-8 of the frame, and positioned above the axis of the supporting member 10, is a trip device designated generally as T. This trip device essentially comprises a suitable bracket 30 having therein a yieldable abutment member 31, which is provided with an abutment head 32 located directly in the path of movement of the head 17 of the supporting member 10, whereby the end 22 of the latch dog 20 carried thereby will engage the said head. That is to say, the yieldable abutment 32 is so arranged with respect to the supporting member 10 that when the same is caused to rotate on its axis 9 under the influence of the spring 14, the end 22 of the latch dog 20 will be brought against the head 32 of the trip device, thereby rocking the latch dog against the tension of the spring 22 to disengage the latch shoulder 21 of the member 20 from the keeper shoulder 26 of the socket element. This trip device is preferably adjustably secured between the arms 8-8, as will be observed from the drawings. To provide for this adjustable mounting, the opposite walls 55 are preferably provided with suitable openings, to permit of the relative position of the trip device to be changed to suit various requirements and conditions, whereby the latch will be operated sooner or later within 60 the limit of movement of the supporting member, as circumstances may require.

From the foregoing it will be understood that the socket element 23 which carries the trolley pole or standard 24 is hinged or pivoted to the supporting member 10 as at 18,

and is held in its normal position with respect thereto by means of the latch dog 20 engaging the keeper shoulder 21. When the parts are in this condition, that is when the socket piece is locked with the supporting member 10, the entire trolley pole is in its normal useful position, as shown in Fig. 1. In other words, with the socket piece and supporting member locked together, the spring 14 exerts its full force on the coupled members 10 and 23 to hold the trolley wheel 25 on the conductor C. However, when the trolley wheel leaves the conductor and the pole jumps upward, under the influence of the spring 14, both the coupled 75 socket 23 and supporting member 10 rotate together until the end 22 of the latch dog 20 strikes against the yielding abutment 32. Then the latch shoulder 21 becomes disengaged from the keeper shoulder 26, as shown 80 in Fig. 2, and the trolley pole or standard drops to a substantially horizontal safety position, as shown by the dotted lines in Fig. 2.

When the trolley pole reaches the limit 90 of its upward movement and is substantially vertical, the spring 28 comes into play to positively swing the socket element on the hinge 18 and pull it to a safety position without relying on the weight of the pole 95 to bring it down, thereby positively preventing the same from striking any of the trolley wire supports or cross arms of the trolley plates. After the latch dog 20 has been released from its engagement with the keeper shoulder 26, and the trolley pole is in its fallen or substantially horizontal safety position, it will of course be apparent that the pole may be again made ready for use by compressing the spring 14 and rotating the supporting member 10 on its axis 100 9 a sufficient distance to permit the dog to again engage the shoulder.

Without further description it is thought that the many features and advantages of the invention will be readily understood, and it will of course be apparent that changes in the form, proportion and minor details of construction may be resorted to without departing from the spirit of the 110 invention or scope of the appended claim.

I claim:

A trolley retriever including a rotatably supported frame having opposite side walls, a pole supporting unit consisting of a pivot 120 section including an enlarged body portion journaled in the side walls of the frame and having oppositely disposed portions one of which constitutes a spring abutment while the other carries hinge knuckles, and 125 a pole receiving socket section also having hinge knuckles for coöperating with the knuckles on the pivot section to constitute a hinged connection therebetween, a pivoted latch carried by the pivot section, a keeper 130

on the socket section for coöperating with said latch, an offset bracket arm also on the socket section on the side opposite the keeper, a spring connecting the extremity 5 of the bracket arm with the enlarged portion of the pivot section, a yielding abutment located in the path of movement of the pivoted latch, and a compression spring arranged between the walls of the frame and

exerting pressure on the abutment end of 10 the pivot section.

In testimony whereof I hereunto affix my signature in the presence of two witnesses.

ELBY A. MORRIS.
